LAWN MOWER

Karl Albert Caspersson, Alsten, Stockholm, Sweden, assignor to Aktiebolaget Superior, Stockholm, Sweden, a corporation of Sweden

Application July 1, 1938, Serial No. 217,033
In Sweden December 8, 1936

7 Claims. (Cl. 56—294)

My invention relates to lawn-mowers of the class in which movable knives are arranged to circle in relation to the stationary knife for cooperation therewith.

5 The main object of the invention is to improve mowers of the type referred to and to remove certain drawbacks of mowers heretofore used. In conventional mowers of said type the circling knives are fixed to the rotary element or elements by which they are carried. In cross-section the plane sides of the knives coincide or 10 approximately coincide with the rotation surface along which the knives move during their circling motion. When a knife fixed as referred to 15 descends from a point on a level with the centre towards the stationary knife the plane of the knife is successively changed from a substantially vertical position to a substantially horizontal position. As a result the knife hits the grass 20 by its outer face due to this change of position whereby the grass is deflected forwardly and escapes cutting or takes a position which is disadvantageous for the cutting operation. Due to 25 the improvement effected by my present invention this draw-back is removed.

A further object of my invention is to provide for a certain movement of the movable knives, in addition to the circling movement thereof in order to obtain a more efficient cutting operation 30 than in conventional mowers.

The invention provides a mower of a construction in which the stationary knife or cutter-bar is combined with movable knives for cooperation therewith, and includes means to impart circling motion to the movable knives, and guide means 35 to cause said movable knives to rotate about their longitudinal axis simultaneously with their circling motion.

40 The invention further consists in the particular construction, arrangement of parts, and combinations thereof hereinafter described and claimed.

An embodiment of the invention is shown by 45 way of example in the accompanying drawings in which

Figures 1, 2, 3 and 4 illustrate the means effecting the knife movement and its operation diagrammatically; Figs. 1 and 2 are cross-sectional views, and Fig. 3 is a part-sectional view; Fig. 4 is a detail view.

50 Fig. 5 is an elevation of a lawn-mower constructed according to the invention.

Fig. 6 is a part cross-sectional view of the machine illustrated in Fig. 5.

Fig. 7 is a part-sectional view of the machine as seen from the rear.

Fig. 8 is a horizontal sectional view of one lateral portion of the machine.

Fig. 9 shows a knife in elevation.

Fig. 10 is a part-sectional view of a modified form of guide means for the knives.

In the diagrammatic Figures 1-4, the numeral 1 designates the shaft about which the knives 2 circle. Preferably, each knife has its bar-shaped rear edge portion 3 journalled rotatably relatively to two arms 4 and 5 secured to the shaft 1 and spaced apart a quarter of a revolution relatively to each other. The knife 2 will thus have a longitudinal inclined position which is required 15 for the cutting operation. Fixed on a trunnion 6 extending from the end of the knife through the arm 4 is a bell-crank lever 7 and journalled thereon is a roller 8 which is adapted to move in a circular groove 9 in a stationary element 10. 20 The groove 9 is eccentric relative to the shaft 1, the eccentricity being equal to the radius of the bell-crank lever 7. The last-mentioned arrangement provides for the guidance of the knives referred to, as will be described hereinafter. 25

The position of the arm 4 marked by *a* in Fig. 1, and the bell-crank lever 7 turn the knife 2 to a position most suitable for the cutting operation. When the arm 4 moves from the position *a* to the position *b* in a direction as shown by the arrow 11, the roller 8 moves in the groove 9 and as a result the bell-crank lever 7 and the knife secured thereto are forced to rotate in relation to the arm 4. Since the radius of the bell-crank lever and the eccentricity between the shaft 1 35 and the groove 9 are equal, the bell-crank lever and the knife maintain the angular position relatively to the horizontal line shown in the position *a* of the arm 4. In the angular position *c* of the arm 4 the knife maintains the same position and effects the cutting operation by engagement with the stationary knife 12 in such position. In the position *d* of the arm 4 and in the position *e* the knife still maintains the same angular position. The plane of the knife thus 40 maintains the position suitable for the cutting operation during the whole revolution. The knives thus maintain a constant angular position relatively to the horizontal line and have their cutting edges directed downward or inclined downward. The knives are advanced between the grass-stalks with their edges foremost and have no tendency of unduly deflecting the grass, and no difficulty is experienced in cutting relatively high grass. After cutting the knives 45

55

ascend, maintaining the position referred to they will act as shovels on the grass which has been cut and throw it rearwardly for collection in a magazine or basket arranged in the mower in a conventional manner. Consequently, the usual disadvantage that the grass which has been cut is carried along by the knives is prevented.

The oblique position of the knife shown in Fig. 3 is necessary as already stated above to obtain a good shearing action against the stationary knife 12. The cutting operation in fact takes place in such a manner that the circling knife initially hits the stationary knife at one end thereof, and the point of contact between the knives then moves therealong successively during the movement. This and the fact that the knives 2 maintain their angular position during the circling movement require an arc-shaped form of the knife edges, as shown in Fig. 3.

A particular advantage of the described arrangement of the movable knives relatively to the stationary knives is that during the cutting operation the movable knife in its cooperation with the stationary knife, in addition to the shearing action which is present for example in usual scissors, performs such a cutting action which occurs for example in using a carving knife because the edge of the movable knife moves longitudinally relatively to the stationary knife to a certain degree during each revolution. This feature will be clear on considering the movement of a point of the movable knife edge during one revolution, as for instance the point *x* in Fig. 3. After the knife has rotated one half revolution from the position shown in full lines to the position shown in dotted lines in Fig. 3, the point *x* has rotated to a position marked *x'*, and simultaneously has moved laterally a distance *y*. This lateral or axial movement of the knife edge relatively to the main shaft 1 is directed toward the point of intersection between the edges of the stationary knife and the movable knife when said knives are cooperating, and as a result the movable knife tends to catch the grass between the knives and pull it into the angle therebetween. The relative movement of the knives as described is favourable to the cutting operation.

The mower constructed for use as shown in Figs. 5-9 corresponds in all essentials to the diagrammatic Figures 1-4, Fig. 5 illustrating an assembly of the mower construction on a reduced scale. Consequently, 1 designates the shaft about which the knives 2 circle. The arms 4 and 5 carrying the knives are shown in Figs. 7 and 8. The bell-cranks connected to the arms 4 and rotatable in relation thereto are designated by 7 and the rollers by 8. The guide groove 9 for the rollers is formed in the stationary frame 10 of the mower. The stationary knife 12 is clamped on an adjustable element in a conventional manner. The shaft 1 is carried by ball bearings 16 in the frame 10 as shown in Fig. 8. One of the ground wheels 17 of the mower has formed thereon an internal gear 18 which meshes with a pinion 19 keyed to the shaft 1. A ground roll 20 of conventional type supports the rear portion of the mower. In order to permit the rear edge portion 3 of each knife 2 to be pivoted in the arms 4 and 5 each knife has, at one end thereof, a trunnion 6 extending through the arm 4, and at the opposite end a tapering hole 21 engaged by the end of an adjustable set screw 22 as shown in Fig. 7. This screw permits the knife to be easily removed and mounted in place and also to

set it in a position so as to prevent any undue slack and clearance during the rotation.

A construction of the groove 9 to fit exactly to the rollers 8 would cause considerable friction when the rollers move in the groove. Such friction may be avoided by constructing the guide means as in the modification shown in Figure 10. The single roller is replaced in this construction by two rollers 8a and 8b one engaging the outer wall 9a of the groove 9, and the other engaging 10 the inner wall 9b thereof. It will be noted that the walls 9a and 9b forming races for the rollers 8a and 8b converge outwardly, and that the diameter of the one roller, 8b, is larger than that of the other roller, 8a. The construction permits 15 the rollers to be set in correct position for rolling against the walls of the groove by axial displacement of the shaft 3 of the knife such axial displacement being effected by means of a set screw as described with reference to the element 22 in 20 connection with the foregoing embodiment.

The invention is not limited to the exact construction shown in the drawings and described with reference thereto but may be modified in comparison therewith in several respects within 25 the scope defined by the claims.

What I claim is:

1. In a lawn mower, a fixed cutter bar, a plurality of knives, rotatable means supporting said knives in circumferential spaced relations 30 to be moved successively adjacent the cutter bar, each knife being longitudinally rotatable with respect to said supporting means, fixed guide means, and means associated with each knife and said guide means for rotating the knives with 35 respect to said supporting means during rotation thereof.

2. In a lawn mower, a fixed cutter bar, a rotatable reel shaft, arms carried by said reel shaft, a knife carried by the arms and mounted 40 for longitudinal rotation with respect thereto for cooperation with the cutter bar, guide means arranged eccentrically with respect to the axis of said reel shaft, and means carried by said knife engaging said guide means for rotating 45 said knife longitudinally during rotation of the reel shaft.

3. In a lawn mower, a fixed cutter bar, a plurality of knives, rotatable means supporting said knives in circumferential spaced relations to 50 be moved successively adjacent the cutter bar, each knife being longitudinally rotatable with respect to said supporting means, fixed circular guide means arranged eccentrically with respect to the axis of said rotatable supporting means, 55 and a bell crank lever carried by each knife engaging said guide means for rotating the knives with respect to said supporting means during rotation thereof.

4. In a lawn mower, a fixed cutter bar, a 60 plurality of knives, rotatable means supporting said knives in circumferential spaced relations to be moved successively adjacent the cutter bar, each knife being longitudinally rotatable with respect to said supporting means, fixed circular 65 guide means arranged eccentrically with respect to the axis of said rotatable supporting means, a bell crank lever carried by each knife engaging said guide means for rotating the knives with respect to said supporting means during 70 rotation thereof, and the radius of said bell crank levers being equal to the eccentric displacement of the guide means with respect to the axis of the rotatable supporting means.

5. In a lawn mower, a frame, a cutter bar 75

fixed to the frame, rotatable means supporting said knives in circumferential spaced relations to be moved successively adjacent the cutter bar, each knife being longitudinally rotatable with respect to said supporting means, said frame having a circular groove therein arranged eccentrically with respect to the axis of said rotatable supporting means, a bell crank lever secured to each knife, and a roller carried by each bell crank lever each engaging said groove for rotating each knife with respect to said supporting means during rotation thereof.

6. In a lawn mower, a frame, a cutter bar fixed to the frame, rotatable means supporting said knives in circumferential spaced relations to be moved successively adjacent the cutter bar, each knife being longitudinally rotatable with respect to said supporting means, said frame having a circular groove therein arranged eccentrically with respect to the axis of said rotatable supporting means, a bell crank lever secured to each knife, a roller carried by each bell crank

lever each engaging said groove for rotating each knife with respect to said supporting means during rotation thereof, and means for axially adjusting the positions of said knives and bell crank levers with respect to said groove.

7. In a lawn mower, a fixed cutter bar, a rotatable reel shaft, circumferentially spaced arms carried by said reel shaft, a knife blade having an arcuate shaped cutting edge carried by two circumferentially spaced arms and mounted for longitudinal rotation with respect thereto for cooperation with the cutter bar, guide means arranged eccentrically with respect to the axis of said reel shaft, and means carried by said knife engaging said guide means for rotating said knife longitudinally during rotation of the reel shaft, whereby the arcuate shaped cutting edge of the knife blade moves longitudinally with respect to the fixed cutter bar during rotation of said reel shaft.
